SURGICAL GLOVE WRAP

Arthur J. Langdon, East Hampton, Conn., assignor to
Edward Weck & Company, Inc., Long Island City,
N.Y., a corporation of Delaware

Filed Feb. 25, 1964, Ser. No. 347,267
5 Claims. (Cl. 229—87)

This invention relates to a glove packaging device and more particularly to a disposable wrapper arrangement for retaining surgical gloves or the like during routine preliminary handling and during sterilization treatment. Thereafter the sterile condition of the gloves and package may be conveniently maintained until such time as they are used.

Although hospital practices are quite varied, the handling of surgeons' gloves generally involves a first cleaning after use and sterilization at some time before reuse. The prior art amply illustrates a technique which involves first packaging the clean gloves in a disposable wrapper, usually made of paper, so that gloves may be transported and stored in a convenient manner. At the appropriate time, the packaged gloves are autoclaved or otherwise rendered sterile for surgical use. When needed, the surgeon or aide will open the package in the surgical preparation area. The many advantages of this procedure have been so well established that further discussion of the handling details is unnecessary.

The glove wrapper itself must meet certain minimum specifications; thus the wrapper must provide a package which is easily and simply manipulated, both during packing and when opened for use, and must permit free penetration of the sterilizing agent. The package when closed must be capable of being stored in little space and must permit ready identification to the potential user. During handling the gloves must be maintained thoroughly sterile, while the mode of packing must prevent accidental exposure of either or both gloves. It is self-evident that any disposable article must, for hospital use, also be economical of manufacture and sale. Prior glove wrappers are generally complex in form, and often failed to meet the exacting demands of hospital practice.

In my prior Patent No. 2,915,173, issued on December 1, 1959, I described a useful glove wrapper. This subject application represents an improvement over my aforementioned patent and provides all of the prior advantages together with features which heretofore were unavailable.

It is therefore an important object of the present invention to provide an improved disposable wrapper for surgical gloves capable of holding the gloves during the sterilization process and capable of securely maintaining the gloves in wrapped sterile condition until use;

Another important object of the present invention is to provide an improved wrapper for surgical gloves that is easily opened for the glove removal when use is contemplated.

Still another important object of the present invention is to provide an improved wrap for surgical gloves wherein the package itself retains the gloves and which prevents unwanted slipping when the wrap is uncovered.

Yet another important object of the present invention is to provide an improved disposable wrap for a surgical glove that is noted by ease of handling throughout, while being exceedingly economical of manufacture, even in limited production quantities.

In accordance with the concept of my invention, an improved wrapper for surgical gloves is formed of a single sheet of paper that is divided into four substantially equal, parallel panels by three vertical fold lines. The two outermost panels are formed with perforated tear lines for easy access to the gloves while the lower edges of the two central panels have gummed areas enabling the forma-

2

tion of pockets for holding the gloves. The improved wrapper for surgical gloves is capable of withstanding the heat and/or pressure required for sterilization in an autoclave, while being adapted to maintain the gloves in a clean sterile condition to the very instant of use.

The features of my invention which I believe to be novel are set forth with particularity in the appended claims. My invention itself, however, both as to its organization and method of use, together with further objects and advantages thereof may best be understood by reference to the following description taken in conjunction with the accompanying drawings in which:

FIG. 1 is a plan view of a paper blank from which a wrap for surgical rubber gloves may be formed in accordance with the present invention;

FIG. 2 is a plan view of the wrap formed from the blank of FIG. 1 and shown in its position after the outer panels are folded over and the bottom gummed portion folded up to form the pocket;

FIG. 3 is a plan view of the wallet shaped wrap formed from the blank of FIG. 1 showing an intermediate folding step;

FIG. 4 is a perspective view of the wrap formed from the blank of FIG. 1 showing the final folded position of the wrap prior to sterilization; and

FIG. 5 is a plan view of the wrap formed from the blank of FIG. 1 showing the gloves in their exposed position, after sterilization, ready for use.

Referring now to FIG. 1, it will be seen that my wrap for surgical gloves is, in accordance with my invention, formed of a generally rectangular sheet of paper 10. The sheet 10 is divided into four approximately equal sections 12, 14, 16 and 18 by three spaced apart vertical fold lines 20, 22 and 24 with fold line 22 being centered with respect to the opposite parallel edges of sheet 10, and with the fold lines 20 and 24 being laterally centered between the central fold line 22 and the vertical side edges of sheet 10.

The sheet 10 forming the blank of FIG. 1 further has a fold line 26 extending laterally to define a lower edge when the gloves are inserted, and an upper parallel fold line 38 spaced a distance away from fold line 26 approximately equal to the length of a surgeon's cuffed rubber glove.

Panel 18 is provided with a tearable perforated line 46 and a tab line 42, the latter of which may be scored or marked for ease in folding. Similarly, panel 12 is provided with a tearable perforated line 48 and a tab line 44 formed in the manner of opposite tab line 42. The areas 34 and 36 of outer panels 18 and 12 respectively, which fall below fold line 26 cooperate with gummed portions, as will be described.

Left central panel 14 is provided with a gummed area 28 lying below the fold line 26 while right-central panel 16 is provided with a pair of gummed portions 30 lying on each side of a blank ungummed central portion 32. It will be noted that panels 12 and 18 are undercut immediately below areas 36 and 34 respectively. This facilitates the sealing process which is to be described.

In forming a wrap for surgical rubber gloves from the single blank sheet 10 described above, the sheet 10 is first folded along lines 20 and 24 so that panels 12 and 18 overlie panels 14 and 16 respectively, while portion 36 of panel 12 overlies area 28 of panel 14 and portion 34 of panel 18 overlies the gummed and blank sections 30, 32 of panel 16. The next folding operation is performed along the entire line 26, which folds the gummed portions 28 and 30 onto the reverse side of panels 12 and 18 respectively. With the gum in sticky condition, the inner faces of areas 34 and 36 are sealed to the upper portions of gummed areas 28, 30 and 32, while the reverse faces of panels 12 and 18 in the regions immediately above

areas 36 and 34 respectively are secured by the lower portions of these gummed areas.

Having thus folded the blank sheet 10, the wrap will now appear as shown in FIG. 2. In this FIG. 2, gloves 40a and 40b have been shown, in outline fashion, inserted between panels 18-16 and 14-12 respectively. As will be noted later, the gloves are not actually inserted until the package is completed; however, the glove outlines are illustrated in FIG. 2 to furnish an indication of relative size and position.

The portion of perforated line 48 lying immediately below the scored portion 44 may be separated to form a generally triangular tab and in a similar manner, the like portion of perforated line 46 lying below the scored line 42 may also be separated to form a second triangular tab. In an arrangement such as this, when the gummed portions 28 and 30 are secured, an open ended pocket 32a is formed which may be used for the insertion of a small packet of powder to be used in the customary manner by the wearer of the gloves.

Referring now to FIG. 3, the wrap is then folded down along line 38. In this figure panels 12, 14, 16 and 18 are illustrated in detail as well as the pocket 32a formed by the gummed portions.

Referring now to FIG. 4, the completed wrap is shown, folded along lines 22 and 38, and ready for use. It should be observed that the wrap may be provided with printed matter 50 on one or both of the outer surfaces thereof which indicates that the contents of the wrap are surgical gloves, it may also indicate glove size as well as any desired instructions or the like. An interesting feature which may be utilized to good advantage lies in the fact that the printing 50 may be of an ink that changes color when subjected to heat during sterilization. In its changed color, the written matter is an excellent, affirmative indication of whether or not the material contained within the wrapper, such as the glove pair, has been sterilized. Indeed the printed matter on the front panel may state the color for the unsterile condition and the color after sterilization.

Through the aid of FIGS. 1 to 4 inclusive, it has been shown how the initial gummed paper blank is formed into a glove wrapper. The completed glove wrapper is made available for hospital use in the form shown in FIG. 4. It is at once apparent that the glove wrapper is thus capable of being packaged, shipped and stored in large quantities with minimum space and cost.

In general, the surgical gloves are packaged in the wrapper shown in FIG. 4 at the hospital by a nurse or aide. For this process, the wrapper of FIG. 4 is first unfolded, as shown in FIG. 3, and then further unfolded to the configuration shown in FIG. 2. Here the panels 12 and 18 are lifted and the gloves inserted flat in the manner best illustrated in FIG. 2. A small package of glove powder (not shown) may also be inserted in the convenient pocket provided therefor, depending upon the practice of the particular hospital involved.

The glove wrapper is then refolded, first to the condition shown in FIG. 3 and finally to the closed condition shown in FIG. 4. When the wrapping operation is completed the gloves are not only retained flat, but also, as is self-evident, the gloves are securely positioned in the wrapper under multiple folds of paper in a manner which precludes accidental exposure or dislodgement.

Gloves packaged as in FIG. 4 may be stored permanently with the assurance that they will remain thoroughly clean and dust free. During the sterilization process, the gloves are autoclaved within the folded wrapper and are delivered to the surgeon for use in packaged form. The surgeon or aide will then unfold the wrapper, preferably upon a flat table surface, to the condition shown in FIG. 2. By grasping the two triangular tabs formed beneath the score lines 42 and 44, the panels 12 and 18 may be opened to the condition shown in FIG. 5 by simply further tearing the paper along perforated lines 46 and 48. From FIG. 5

it is clear that this operation exposes the gloves, still securely held within the lowermost pockets, for use by the surgeon, as required. After use the wrapper is thrown away.

The triangular pull-tabs formed immediately beneath the score lines 42 and 44 may be formed by the partial tearing operation along tear lines 46 and 48 respectively at the time of manufacture. Alternatively these tabs need not be formed during manufacture but a suitable instruction may be printed upon the wrapper so that the nurse or aide who first inserts the gloves may perform this intermediate step. Finally, the tabs need not be formed until the glove package is actually first opened after sterilization.

As has been mentioned earlier, the formation of a pocket for a glove powder package is optional. If a particular hospital does not wish to prepackage glove powder with each pair of gloves, then the small pocket 32a will not be utilized. Thus under some circumstances it may be desirable to apply gum to the area 32 shown in FIG. 1. This procedure will entirely eliminate the pocket 32a.

While I have described what is presently considered to be a preferred embodiment of my invention, it will be obvious to those skilled in the art that there are other changes and modifications which may be made therein without departing from the inventive concept contained therein. Therefore the appended claims are intended to cover all such changes and modifications that fall within the true spirit and scope of my invention.

What is claimed is:

1. A disposable wrap for retaining surgical gloves during and after sterilization comprising, a unitary sheet formed with two substantially equal central sections foldably joined to each other along a central fold line and two outer sections foldably joined to said central sections along the edges of said central sections remote from said central fold, said outer sections being folded over against said central sections to dispose free outer edges closely adjacent said central fold; a flap portion along the lower extremities of the two central sections folded over along a first transverse fold line and sealed to the lower outer surface of said two folded over outer sections; tear line perforations extending transversely across said outer sections adjacent the free edges of said flaps; a second transverse fold line extending across said wrap at right angles to said section fold lines a distance somewhat greater than a glove-length from said flat-sealed end, the free end of the wrap adjacent said second transverse fold line being folded thereover against the upper outer surface of said outer sections, said wrap being folded along said central fold line thereby disposing the outer surfaces of said outer sections against each other.

2. A disposable wrap for retaining surgical gloves during and after sterilization comprising, a unitary sheet formed with two substantially equal central sections foldably joined to each other along a central fold line and two outer sections foldably joined to said central sections along the edges of said central sections remote from said central fold, said outer sections being folded over against said central sections to dispose the free outer edges closely adjacent said central fold; a flap portion along the lower extremities of the two central sections folded over along a first transverse fold line and sealed to the lower outer surface of said two folded over outer sections; tear line perforations extending transversely across said outer sections adjacent the free edges of said flaps; means for forming pull tabs upon tearing a limited portion of said tear perforations from said free edges of said outer sections; a second transverse fold line extending across said wrap at right angles to said section fold lines a distance somewhat greater than a glove-length from said flat-sealed end, the free end of the wrap adjacent said second transverse fold line being folded thereover against the upper outer surface of said outer sections, said wrap being folded

along said central fold line thereby disposing the outer sections against each other.

3. A wrap as in claim 1 wherein said flap portion along the lower extremities of said central sections is gummed to form said seal.

4. A wrap as in claim 3 wherein said gummed flap portion extends outwardly of said unitary sheet beyond the adjacent edges of said central sections, whereby said gummed flap portion forms said seal with both surfaces of outer sections.

5. A wrap as in claim 4 wherein said flap portion is

formed with an ungummed section between gummed portions thereof, said seal thereby defining a pocket for retaining a package therein.
